FRANKLIN D. THOMAS, OF SAGINAW, MICHIGAN.

ROTARY GAS-ENGINE.

987,929.

Specification of Letters Patent. Patented Mar. 28, 1911.

Application filed May 1, 1909. Serial No. 493,431.

To all whom it may concern:

Be it known that I, FRANKLIN D. THOMAS, a citizen of the United States, residing at Saginaw, in the county of Saginaw and State of Michigan, have invented certain new and useful Improvements in Rotary Gas-Engines; and I do hereby declare the following to be a full, clear, and exact description of the invention, such as will enable others skilled in the art to which it appertains to make and use the same.

My invention relates to rotary engines.

The style of engine herein described and illustrated is the internal combustion type but it is obvious that it might be operated by compressed air or steam.

The objects are to provide a perfectly balanced and noiseless engine which is economical in operation and which will develop a greater amount of power than can be obtained by any other engine having the same piston area.

Another object is the provision of a reversible engine.

A further object is the provision of an engine which can be easily and quickly assembled and disassembled, of simple and compact form with no expensive parts or complicated features and practically valveless.

A still further object is the provision of an engine which shall utilize the maximum expansion of the motive fluid.

Still another object is the provision of an engine in which there is no back pressure, and a minimum of friction and lost power.

Another object is the provision of an engine having a novel system of lubrication and one in which there is a perfect combustion and no back firing.

To these and other ends, therefore, my invention consists in certain other novel features and combinations such as will be more fully described hereinafter and particularly pointed out in the claims.

In the accompanying drawings, Figure 1 is a vertical sectional view partly in full lines through a machine embodying my invention, Fig. 2 is a cross-sectional view on line $x-x$ of Fig. 1, Fig. 3 is a detail top plan view of the working parts removed from the cylinder, Fig. 4 is a view in side

elevation, Fig. 5 is a detail view showing the yoke which controls the locking and unlocking of the drums and their respective sections, and Fig. 6 is a detail view of such yoke viewed from the edge.

As shown, the invention consists of a rotary internal combustion engine embodying novel means whereby the direction of rotation of the pistons of which can be easily and quickly reversed.

A indicates a water jacketed circular cylinder formed preferably in halves and provided with the flanges 1, secured together by means of the cap screws 2. The opposite side faces of the cylinder are provided with the openings 3, 3 and carry the semi-circular flanged casings 28. The cylinder chamber is preferably circular and contains the pistons which are exact duplicates so that a description of one will suffice for both. Each piston 4 and 5 consists of a centrally apertured annularly flanged disk, the disks arranged so as to form an internal chamber 6, the free edges of the flanges abutting to form a sliding joint. The flange of each disk is equipped with a pair of diametrically opposed wings 7, 8, 9 and 10, projecting from the periphery thereof, the wings extending across the cylinder from side to side. The wings on one flange project over the periphery of the flange of the opposed piston, and each wing is grooved along its opposite ends to receive packing rings 11, which engage the opposite heads of the cylinder. Those portions of the under surfaces of the wings which overlie and rotate relative to the opposed pistons are grooved as indicated at 12, to receive packing and the outer edges of the wings are similarly grooved to receive packing 13 which engages the inner periphery of the cylinder.

Located at some convenient point in the periphery of the cylinder are the interchangeable inlet and exhaust ports 14 and 15, spaced apart from each other as shown, and preferably diametrically opposite thereto are the ports 16, 16', which receive the spark plugs 17, 17', such ports likewise spaced apart from each other. A casting 18 is secured to the cylinder, the casting provided with passages registering and forming continuations of the interchangeable inlet and

exhaust ports, such passages leading to a valve seat in which is received the hollow reversing plug valve 19. This valve is provided with a peripheral groove 20 extending semi-circumferentially thereof and adapted to connect one or the other of the ports 14 or 15 with a chamber 21 in the casting with which one or more carburetors (not shown) may communicate. The hollow interior of the plug valve communicates by means of a lateral opening 22 with the exhaust port, the hollow interior discharging into an outlet 23 in the casing. The respective spark plugs 17, 17' are connected to a high tension switch 24 of any usual construction, operated by a shaft 25, for cutting the current over from one spark plug to the other in reversing the engine, 26 indicating the binding posts for the battery connections.

Projecting laterally from the pistons 4 and 5, through the openings 3 of the cylinder, are the hollow drums 27, 27' arranged concentrically relative to the shaft apertures 25 of the pistons, and themselves provided with apertures registering with those in the piston disks. These drums are inclosed in the semi-circular flanged casing 28, bolted to the respective side faces of the cylinder, as at 29. The casings are provided with journals 30, 30, which may conveniently comprise the thimbles 31 encircling the bushings 32.

Within the internal chamber 6 is located the means for transmitting the rotary movement of the pistons to the shaft, such means consisting of a differential gearing. The gears 33 and 34 are secured to the inner faces of the respective piston disks, the gears 40 provided with oppositely extending sleeves 51 passing through the centrally disposed apertures in the pistons and drums and through the bushings 32 of the journals. A shaft 35 is loosely received in the sleeves, and a carrier 36 is keyed to that portion of the shaft within the internal chamber 6 and between the gears 33 and 34, such carrier having the diametrically projecting pintles 37 thereon, on which are journaled the pinions 38 meshing with the gears 33 and 34. It will thus be seen that the rotation of the pistons will rotate the gears 33 and 34 carried thereby, such rotation being transmitted to the shaft 35 through the pinions and carrier. It is necessary, however, in operating this construction as a rotary internal combustion engine, that means be provided to automatically lock the piston alternately in order that the wings of the locked pistons may serve as stationary abutments, and to this end I provide the drums 27, 27' in the casings 28. Grooves 39 are arranged peripherally of the drums, such grooves each being offset laterally at two diametrically opposite points. The offsets consist of the steps 40 and 41,

the latter being combined and registering with pockets 42 formed in the inner walls of the groove, the outer walls of the grooves being provided with double cams whose faces 43 lie opposite the steps 40, the peaks 44 of 70 the cams lying opposite the steps 41. These offsets lie in alignment with the wings of the respective pistons and rotate therewith.

U-shaped yokes 45, 45' carry the offset trunnions 46 which are journaled in the 75 flanges 47 of the casings, the yokes partially encircling the drums. One trunnion on each yoke is extended beyond the flanges of the casing and carries a crank 48, the cranks being connected by a rod 49 so that movement 80 of one yoke is communicated to the opposite yoke. Each yoke carries a roll 50, 50' received in the groove 39. The lodgment of the roll in either of the pockets 42 of its groove operates to lock the drum and piston 85 against rotation and simultaneously releases the opposite drum and piston to permit the rotation of the latter.

The operation of my invention is as follows: The piston 4 carrying the wings 7 and 8 is held in locked position by the roll 50 which lies in the step 41 and pocket 42 of the drum 27. The reversing and combined inlet and exhaust valve 19 is in the position shown in Fig. 2, wherein 14 is the inlet port 95 and 15 the exhaust port. The wings 9 and 10 of the piston 5 being in the positions shown in Fig. 2, a combustible charge is under compression between the fixed wing 7 and the movable wing 9. The charge being 100 ignited from the spark plug 17, the expansion drives the wings 9 and 10 and their piston 5 throughout a half revolution in the direction of the arrow, such movement of the piston 5 rotating the gear 34 throughout 105 one-half a revolution and the latter rotating the pinions and hence, the shaft 35 to which they are secured through a quarter of a revolution. From this it will be seen that I double the force communicated to the shaft 110 through half a rotation of the piston. Hence, a full rotation of the piston will quadruple the force imparted to the shaft. The movement of the wing 9 in the direction 115 of the arrow operates to scavenge the annular piston chamber, driving the products of combustion of the charge last exploded, out of the chamber into the exhaust port 15 and thence through the opening 22 into the hollow plug and the exhaust opening 23. Meanwhile, the wing 10 moves upward in the direction of the arrow and operates to draw in a charge behind it through inlet port 14, groove 20 and chamber 21. It also compresses 120 between itself and the locked wing 7, the charge previously drawn into the piston chamber by the upward movement of the wing 7. The rotation of the piston 5 has rotated its drum 27', the groove 125 39 of which moves relative to the roll 50 on 130

the yoke 45'. As the wings 9 and 10 approach the stationary wings 8 and 7 respectively, the offset portion of the groove 39 nears the roll 50'. Now, at about the time 5 the wing 9 reaches the exhaust port 15, the roll 50' slips into the adjacent step 40 of the offset, being forced thereinto by the face 43 of the opposed cam. This movement of the roll 50' swings the yoke 45' sidewise 10 and through the link 49, such movement is communicated to the yoke 45 and roll 50. Owing to the cranked connection of the yoke with its trunnions, such movement will throw the roll 50 out of its pocket 42, there- 15 by unlocking the piston 4, and the inertia of the moving parts of the mechanism will cause piston 4 to rotate until the roll 50 lies in the step 40 of its groove and thence out into the annular portion of such groove. 20 The movement of the piston 4 from locked to partially unlocked position permits the movement of the pistons 7 and 8 to the positions occupied by the pistons 9 and 10 in Fig. 2, and as the roll 50 moves out into the 25 annular portion of its groove, the continued movement of piston 5 causes the peak 44 of the cam to guide the roll 50' into the step 41 and pocket 42, thereby locking the piston with its wings 9 and 10 in the positions occ- 30 upied by the wings 7 and 8 in Fig. 2, whereupon the foregoing operation is repeated. The provision of the pockets 42 for the rolls 50, 50', while not absolutely essential, constitutes a means for relieving the 35 wall of the groove from wear and reduces the strain on the locking yokes. The sleeves 51 of the gears 33 and 34 extend past the journals 30 of the casings 28, their projecting ends being equipped with spark timers 40 52 of any convenient construction, the contact disks 53 of which coöperate with the contacts 54 being actuated by arms 55 connected by links 56 and cranks 57 to a shaft 58 controlled by a lever 59. By means of 45 this construction, the ignition of the charge may be timed to take place at any point in the stroke or travel of the wings.

The engine is easily reversed and as one means for accomplishing this end, I provide 50 the stem 60 of the valve 19 with a gear 61 in mesh with a second gear 62 actuated from the shaft 25 which also controls the high tension switch 24, the shaft being operated by a hand lever 63. Assuming the parts to 55 be in the position shown in Fig. 2, with the charge between wings 7 and 9 about to be ignited. By a movement of the shaft 25, the gears 61 and 62 are operated to partially rotate the valve 19 so that its groove 20 will 60 connect port 15 with the chamber 21, and the exhaust opening 22 will register with port 14. Simultaneously therewith, the electric current will be switched to deenergize spark plug 17 and energize spark plug 17'. 65 The inertia of the engine, together with the

force exerted by the compressed charge against the wing 9, will cause the rotation of piston 5 in the direction of the arrow, and the compression of the charge between pistons 10 and 7. As the wing 10 approaches the wing 7, the compressed charge between those wings is ignited and the shaft rotated in the reverse direction. If the charge between pistons 7 and 9 is ignited, prior to the reversal of the valve, the piston 4 will be 70 released and piston 5 locked, the inertia of the parts then causing wing 8 to move toward wing 10, which at that time will occupy the position of wing 7 in Fig. 2 and the same result take place. There are two 75 charges in the piston chamber at all times, one being compressed and the other under compression.

The lubrication of my engine is accomplished by introducing a quantity of oil into 80 the hollow drums which serve as reservoirs, the oil being splashed onto the sleeves 51 and through the centrally-disposed openings in the drum and in the piston disks, whence it is distributed to the gears and bearings. 85 Other means of lubrication can be utilized, however, without departing from the spirit and scope of my invention, one aspect of which consists in the combination with the rotating pistons, of a gear mechanism 90 arranged as shown and actuated by the pistons. Another feature of my invention consists in the provision of automatic locking means of the type shown, for alternately locking one piston against rotation and releasing the opposite piston. By the use of the four pistons shown, four charges are successively drawn into the annular piston chamber, four compressions take place and an equal number of explosions for each complete rotation of the shaft 35, the pistons making two complete rotations for every single rotation of the shaft. Another advantage gained by my construction is that the upper half of the casing 28 and cylinder 95 A can be removed, thereby disclosing the entire working parts of the engine, by merely taking off the cap screws 2. No tools aside from a wrench are needed to take the engine apart or assemble the same, the drums and pistons with their gears sliding off the shaft, leaving the latter bare with the exception of 100 the carrier.

My invention consists of but few parts 105 which are not liable to get out of order easily, and it is readily assembled by an unskilled laborer. It is light in weight, compact and small. It will be seen that each wing sustains the concussion of the explosion but once in four times, hence, the life 110 of the engine is prolonged. Furthermore, no back firing is possible, owing to the close fit of the wings against the walls of the annular piston chamber, assisted by the packing rings. Also, there is but a minimum of 115

back pressure caused by the compression of the succeeding charge between the upper stationary wing and the succeeding movable wing, and this is the only back pressure which is brought to bear on the shaft. Again, there is but a single valve used in the entire construction and no springs whatever are employed. The valve, except when it is desired to reverse the direction of motion of the shaft, remains stationary and does not operate as a puppet. It will be seen that each wing corresponds to the piston area of an ordinary reciprocating piston engine and that the distance between the spark plug and the exhaust port corresponds to the piston travel of such reciprocating piston engine. However, the length of travel of the wings of my engine is greatly in excess of the length of stroke of the ordinary reciprocating engine, so that I am able to utilize practically all of the pressure generated by the ignition of a charge, whereas in the ordinary reciprocating style of gas engine, fully 40% of the pressure is wasted through the exhaust. By utilizing the pressure generated, I do not require a muffler on my exhaust, as there will be no noise incident to the discharge of the exhaust. In other words, I provide an engine having a comparatively slow but powerful shaft speed, whereas the reciprocating engines sacrifice power for speed.

The ordinary reciprocating engine requires a crank shaft and if more than one engine is used, an expensive crank shaft is necessary in order that the engines may be evenly balanced. My engine is self balanced and requires merely the ordinary straight shaft, as many engines being coupled on the same shaft as are desired. There is no vibration, since the wings travel in a circular path, and no lost power in passing over dead centers. Since the charge is drawn into the cylinder directly from the carburetor and is not forced in by compression, a less amount of fuel is necessary in operating my engine than is required by engines of the reciprocating type.

Having thus fully disclosed my invention, what I claim as new, is:—

1. A rotary engine comprising a cylinder, pistons in the cylinder, wings on the pistons, means for introducing motive fluid between the pistons, a shaft passing loosely through the pistons, gears carried by the pistons, and gears secured on the shaft and meshing with the gears on the pistons.

2. A rotary engine comprising a cylinder, pistons in the cylinder, wings on the pistons, means for permitting successive pistons to draw motive fluid into the cylinder between the piston wings, the motive fluid being compressed by the movement of one piston wing toward the next wing in advance thereof, means for automatically locking one

of the pistons and simultaneously releasing the other piston, a shaft passing loosely through the pistons, gears carried by the pistons, and gears secured on the shaft and meshing with the gears on the pistons.

3. A rotary engine comprising a cylinder having a plurality of ports, a reversible valve having an intake port leading from a source of power and an exhaust opening, means for operating the valve so that the respective intake port and exhaust opening thereof may register with either one of the cylinder ports, pistons received in the cylinder and movable independently of each other, a transmission gearing inclosed by the pistons, and a shaft actuated by the operation of the gearing.

4. A rotary engine comprising a cylinder, a shaft passing therethrough, circular hollow pistons received in the cylinder and movable relative to each other, wings carried by the respective pistons, gears mounted within and fast on the respective pistons, a carrier on the shaft intermediate the piston gears, and pinions journaled on the carrier and meshing with both piston gears simultaneously.

5. A rotary engine comprising a cylinder, a shaft passing through the cylinder, pistons in the cylinder, the pistons rotating independently of the shaft and of each other, wings on the pistons, means for automatically locking one piston and releasing the remaining piston alternately, and transmission gearing carried by the pistons and shaft respectively for increasing the force transmitted from the pistons to the shaft.

6. A rotary engine comprising a cylinder, a shaft passing therethrough, circular flanged pistons received in the cylinder, wings carried by the pistons, the flanges of the pistons engaging throughout their circle, to form a sliding joint, the pistons provided with apertures to receive the shaft, gears secured to the inner faces of pistons, means carried by the shaft and meshing with the gears for transmitting motion to the shaft, sleeves projecting from the gears, the sleeves loosely encircling the shaft, means for introducing successive charges to the cylinder between the wings of the respective pistons, means for exploding the charges, and spark timers on the sleeves of the gears for controlling the time of ignition of the charges.

7. A rotary engine comprising a cylinder consisting of upper and lower sections, means for removably connecting the sections, pistons in the cylinder, wings on the pistons, a shaft passing through the cylinder and pistons, and a differential gear, the elements of which are carried by the pistons and shaft respectively, to transmit the motion of the pistons to the shaft.

8. A rotary engine comprising a cylinder,

- pistons in the cylinder, wings on the pistons, a shaft passing through the cylinder and pistons, a differential gear, the elements of which are carried by the pistons and shaft 5 respectively, to transmit the motion of the pistons to the shaft, and means for locking and releasing the pistons alternately.
9. A rotary engine comprising a cylinder, pistons in the cylinder, wings on the pistons, a shaft passing through the cylinder and pistons, drums carried by the respective pistons, the drums equipped with cam grooves having locking steps, rolls in the grooves, 10 yokes carrying the rolls, means connecting the yokes, and means for transmitting the motion of the pistons to the shaft.
10. A rotary engine comprising a cylinder, pistons in the cylinder, a shaft, means for transmitting the motion of the pistons 20 to the shaft, drums carried by the pistons and having grooves therein, a portion of the grooves being stepped, and a stepped cam located opposite the stepped portion of the groove, rolls received in the grooves, swinging means on which the rolls are received, 25 and a rod connecting the swinging means.
11. A rotary engine comprising a cylinder, pistons therein, a shaft, means for transmitting motion from the pistons to the shaft, drums carried by the respective pistons, the drums having cam grooves formed 30 therein, locking means associated with each cam groove, and a rod connecting the locking means to cause the release of one drum when the other drum is locked.
- 35 12. A rotary engine comprising a cylinder, pistons therein, a shaft, means for transmitting motion from the pistons to the shaft, and means for locking the pistons alternately against movement, such means comprising grooved drums secured to the pistons and projecting laterally through the sides of the cylinder, casings inclosing the drums, yokes having trunnions journaled in the casing, rolls on the yokes received in the cam grooves, and means connecting the yokes.
13. A rotary engine comprising a cylinder, pistons therein, a shaft, means for transmitting motion from the pistons to the shaft, 40 means for alternately locking the pistons against movement, such means comprising drums secured to the pistons and provided with grooves, the inner walls of the grooves being stepped, stepped cams on the outer 45 walls of the grooves opposite the stepped portions of the grooves and co-operating therewith, and connected locking members co-operating with the grooves.
14. A rotary engine comprising a cylinder, pistons therein, a shaft, means for transmitting motion from the pistons to the shaft, 50 means for alternately locking the pistons against movement, such means comprising drums secured to the pistons and provided with offset grooves having pockets formed 55 in the offsets, and inter-connected locking members projecting into the grooves and alternately receivable in the offset pockets.
15. A rotary engine comprising a cylinder having inlet and exhaust ports, a chambered valve casing having ports registering with the cylinder ports, a hollow valve in the casing, the valve having an opening connecting one of the cylinder ports with the hollow interior of the valve and also provided with a passage connecting the remaining cylinder port to the chamber in the valve casing, pistons received in the cylinder, wings on the pistons, spark plugs carried by the cylinder and spaced apart from each other, a switch controlling the energization of the spark plugs, and means for reversing the valve and simultaneously actuating the switch to reverse the direction of rotation of the pistons.
16. A rotary engine comprising a cylinder having interchangeable inlet and outlet ports, a valve casing provided with intake and exhaust ports, a reversible valve for connecting the cylinder ports with the intake and exhaust ports, pistons in the cylinder, wings on the pistons, a shaft, means for communicating the motion of the pistons to the shaft, spark plugs for exploding the charge on either side of a wing, a switch for energizing one or the other of the spark plugs, and means for simultaneously reversing the switch and valve.
17. A reversible rotary engine comprising a cylinder, pistons in the cylinder, wings on the pistons, a shaft arranged concentrically with and passing loosely through the pistons, gears carried by the shaft, other gears carried by the pistons and in constant mesh with the gears on the shaft for transmitting motion from the pistons to the shaft, means for alternately locking the pistons against movement, and means for permitting one piston to have a slight preliminary forward movement prior to its complete release as the next adjacent piston approaches its locking position.
18. A rotary engine comprising a stationary cylinder, pistons in the cylinder, wings on the pistons to turn the latter in the cylinder, means for introducing motive fluid between the wings, a drive shaft passing loosely through the pistons and the cylinder ends, means for transmitting motion from the pistons to the shaft, and means, other than the power transmission means and connected to be controlled by the rotation of the pistons, for automatically and temporarily locking successive pistons against movement in either direction, and releasing the remaining piston for movement.
19. A rotary engine comprising a cylinder, pistons in the cylinder, wings on the pistons, a shaft, means for transmitting motion from the pistons to the shaft, drums on

the pistons, the drums having cam grooves, locking members received in the grooves, yokes carrying the locking members, suitably journaled trunnions offset from the 5 yokes, and means for connecting trunnions on the respective yokes.

20. A rotary engine comprising a cylinder having openings in its sides, flanged pistons in the cylinder, the free edges of the 10 flanges engaging to form a sliding joint, wings on the pistons, a shaft passing through the pistons, gearing inclosed within the pistons for transmitting motion from the pistons to the shaft, hollow grooved drums carried by the pistons and projecting through the openings in the cylinder, and locking means coöperating with the grooved drums to automatically lock the respective pistons alternately against movement, the hollow 15 drums adapted to contain lubricant.

21. A reversible rotary engine comprising a cylinder, pistons in the cylinder, a plurality of wings on each piston, a shaft passing loosely through the pistons, means 25 for transmitting motion from the pistons to the shaft, other means for alternately locking the pistons against rotary movement, a plurality of ignition members located on two opposite sides respectively, of 30 one of the piston wings when the latter is in locked position, the cylinder provided with inlet and exhaust ports located on two opposite sides of the remaining piston wing when in locked position, a valve controlling 35 the inlet and exhaust ports, and means for simultaneously reversing the valve and energizing one or the other of the ignition members to reverse the direction of rotation of the shaft.

40. 22. A rotary engine comprising a stationary cylinder, pistons turning in the cylinder, a rotatable shaft passing loosely through the pistons, wings fast on the pistons, transmission gears carried by the pistons and shaft, whereby motion is transmitted from the pistons to the shaft, the 45 gears on the shaft interposed between the pistons and meshing with the gears on the respective pistons, and locking mechanism to alternately secure one of the pistons against movement in either direction, and to 50 release the remaining piston.

23. A reversible rotary engine comprising a cylinder, pistons rotatable in the cylinder, wings on the pistons, releasable locking means for temporarily retaining successive 55 pistons against movement, the cylinder provided with inlet and exhaust ports, and a reversible valve controlling the admission of motive fluid to the cylinder through either 60 port on one side or the other of a wing.

24. A rotary engine comprising a cylinder, pistons mounted to rotate in the cylinder, a drive shaft passing loosely through 65

the cylinder, transmission gears carried by and directly connecting the pistons and shaft, and locking mechanism controlled by the pistons to releasably and positively lock them successively against rotation in either 70 direction.

25. A rotary engine comprising a cylinder, pistons in the cylinder, a shaft passing loosely through the pistons, intermeshing transmission gears carried by and directly connecting the pistons and shaft, and means other than the gearing for positively locking the pistons successively against rotation in either direction, such means arranged to partially release one piston to permit it to 75 have a slight preliminary forward movement prior to its complete release, as the next adjacent piston approaches the locking 80 position.

26. A rotary engine comprising a cylinder, pistons therein, a shaft, means for transmitting motion from the pistons to the shaft, and means for locking the pistons alternately against movement, such means including grooved drums carried by the pistons, movably supported locking means receivable in the grooves and automatically operating to prevent rotary movement of one or the other of the drums, and means connecting the locking means of the respective 90 drums to effect their alternate operation. 95

27. The combination, in a rotary gas engine, with a cylinder, pistons in the cylinder, wings on the respective pistons, and a shaft passing loosely through the pistons, of 100 intermeshing transmission gears, the component parts of which are carried by the pistons and the shaft respectively, and means for releasably and alternately locking the gear elements carried by the respective pistons against rotation. 105

28. A reversible rotary engine comprising a cylinder, pistons rotatable in the cylinder, wings on the pistons, releasable locking means for temporarily retaining successive 110 pistons against movement, the cylinder being provided with inlet and exhaust ports, and means for controlling the admission of motive fluid to the cylinder through either 115 port on one side or the other of a wing.

29. In a rotary engine, the combination with a stationary cylinder, pistons rotating therein about their own axes, and capable of independent movement, and having wings, a drive shaft passing loosely through the pistons and journaled in the opposite ends of the cylinder, and means to introduce motive fluid into the spaces between the pistons and to exhaust the products of combustion, of transmission gearing connecting the pistons and the shaft, and locking members connected to each other and controlled by the rotation of the pistons to effect the simultaneous locking and unlocking 120 of the pistons alternately. 125

30. In a rotary engine, the combination with a cylinder having inlet and outlet ports leading toward a valve seat, pistons in the cylinder, and a drive shaft driven by the 5 pistons, of a reversible valve in the seat to control the admission of motive fluid to and the escape of the spent gases from the cylinder, said valve comprising a shell having a port on the periphery thereof to connect the 10 inlet port of the cylinder with a source of supply led to the valve, and having a port extending axially therethrough communicating through an opening in the shell of the valve with the outlet port of the cylinder, to convey the spent gases from the cylinder and prevent their contact with the valve seat.
31. In a rotary engine, the combination with a cylinder having inlet and outlet ports 20 leading toward a valve seat, pistons in the cylinder, and a drive shaft turned through the rotation of the pistons, of a reversible valve in the seat to control the admission of motive fluid to and the escape of the spent 25 gases from the cylinder, said valve comprising a shell having a peripheral port to admit the motive fluid to the cylinder inlet port, and an exhaust port separated by the shell from the valve seat and communicating 30 with the cylinder outlet port to provide

for the escape of the spent gases and prevent their contact with the valve seat.

32. In a rotary engine, the combination with a cylinder, pistons in the cylinder, a shaft passing loosely through the pistons, 35 and wings on the pistons, of transmission gearing on the pistons and shaft, for transmitting the rotary piston motion to the shaft, and locking means independent of the gearing for positively and temporarily 40 holding the successive piston wings and their pistons against rotation in either direction, and effective to prevent the contact of the piston wings with each other.

33. In a rotary engine, the combination 45 with a cylinder, and pistons alternately rotatable therein, of a shaft passing loosely through the pistons, opposed driving gears on the pistons, driven gears secured to the shaft, and located between and meshing with 50 both driving gears, and effective both to transmit the motion of the alternately rotating pistons to the shaft, and to reduce the shaft speed while maintaining high power.

In testimony whereof, I affix my signature in presence of two witnesses.

FRANKLIN D. THOMAS.
